UNITED STATES PATENT OFFICE.

RAY C. NEWHOUSE, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

CRUSHER.

Application filed January 3, 1921. Serial No. 434,493.

To all whom it may concern:

Be it known that RAY C. NEWHOUSE, a citizen of the United States, residing at Wauwatosa, in the county of Milwaukee and

5 State of Wisconsin, has invented a certain new and useful Improvement in Crushers, of which the following is a specification.

This invention relates in general to crushers. It may be applied with particular ad- 10 vantage in crushers of the gyratory type.

One of the objects of the invention is the provision of a crusher which may be economically built and which is of minimum size and weight compared to its capacity. A 15 more specific object is the reduction of the height of a crusher of given capacity whereby large amounts of metal may be saved.

Another object is the provision of a more efficient crusher and to this end the provision 20 of means whereby the material crushed may be readily discharged from the crusher, this means being at the same time so constructed as to permit reduction of the height of the crusher while at the same time strengthen- 25 ing the shell thereof; and to the same end, the provision of an efficient lubricating and oil circulating system which is not readily susceptible to failure and is moreover accessible for repairs. Ancillary to an efficient 30 lubricating and oil circulating system, a further object is the provision of means whereby dust may be effectively prevented from entering the lubricating oil and particu- 35 larly the eccentric bearings of the crusher, and means whereby the eccentric and associated bearings and the oil thereon may be cooled.

Other objects will appear hereinafter as the description of the invention proceeds.

40 The novel features of the invention will appear from this specification and the accompanying drawings forming a part thereof and disclosing several embodiments of said invention, and all these novel features 45 are intended to be pointed out in the claims.

Fig. 1 is a vertical sectional view of a crusher embodying the features of the invention.

Fig. 2 is a plan view of the bottom shell 50 of the crusher illustrated in Fig. 1.

Fig. 3 is a front elevation of the bottom shell one half thereof being shown in section, the view being taken along the line III—III, Fig. 2.

55 Fig. 4 is a fragmentary view taken along

the line IV—IV of Fig. 1 and shows a pump in the oil circulating system of the crusher and the manner of driving and mounting the same.

Fig. 5 is a fragmentary detail view of one 60 end of the pump shown in Fig. 4.

Fig. 6 is a vertical sectional view of a crusher of modified form embodying the features of the invention.

Fig. 7 is a plan view of the bottom shell 65 of the crusher illustrated in Fig. 6, the top flange thereof being cut away.

Fig. 8 is a front elevation of the bottom shell illustrated in Fig. 7, one half thereof being in section, the view being taken along 70 the line VIII—VIII looking in the direction of the arrows, the crusher shaft and associated parts being shown in position in said shell.

The crusher illustrated in Fig. 1 comprises 75 a top shell 1 and a bottom shell 2 adapted to support the top shell. A spider 3 is provided for carrying the crusher shaft 4 and parts rotating therewith by means of the suspension collar 5 and the ball and socket 80 6, 7, comprising a suspension bearing. The crusher shaft 4 is provided with a suitable crusher head 8 which in conjunction with the concaves 9 which line shell 1, coact in the well known manner to crush the mate- 85 rial put into the crusher.

With the shaft 4 is associated an eccentric 10 having an inner bearing-surface 11 co-operating with the shaft and an outer bearing-surface 12 co-operating with the 90 outer bearing 13. The bearing 13 is supported by a member 14 provided with depressions 15, 16 here shown as of annular form. These depressions in conjunction with the bearing member 13 form passages 95 in which a cooling fluid as water may be circulated for cooling the bearing and the eccentric. Water may be introduced through a pipe 17 and be caused to circulate through the annular passage 15 and from thence 100 through the annular passage 16 and out of a pipe 18 connected with the latter passage. The bearing supporting member 14 is in turn supported from the shell by a number of strut members one of which 19 is shown 105 in Fig. 1. The member 14 is in addition supported as will hereinafter appear, to resist the great strains put upon it by the eccentric when the crusher is in operation.

The eccentric has a bevel gear 20 opera- 110

tively associated therewith, as by means of the key 21, and the weight of this gear and the eccentric are carried by a wearing ring 22. The wearing ring 22 is supported by a 5 bottom plate 23 which may be bolted to and supported by the bottom shell of the crusher. The bottom plate is here shown as provided with a transversely extending flanged portion 24 for supporting the wearing ring 22 10 and a transversely extending flanged portion 25 by means of which the bottom plate may be fastened to the bottom shell.

The gear 20 is provided with a cover plate 26 which has a downwardly opening central 15 recess 27 with which communicate radial passages 28 having openings 29 in the upper side of the plate. While two radial passages are here shown, any desired number may be utilized. The purpose of the recess and 20 radial passages will be hereinafter set forth.

The gear 20 is here shown as driven by a bevel pinion 30 associated with a crusher driving shaft 31. This driving shaft is supported by a bearing 32. A pump 33 which 25 may be of the rotary gear type is mounted in the housing of the bearing 32. This pump is provided with a shaft having ends 34, 35 extending in opposite directions out of the casing of the pump. A pinion 36 is 30 adapted to be keyed to either the end 34 or the end 35 of the pump shaft. The pinion 36 is here shown as driven by a gear 37 rigidly associated with the driving shaft 31. The pump casing is provided with a cylindrical portion 38 adapted to be journaled in a hole 39 in a wall 40 forming part of the bearing housing. The other end of the pump casing projects through a hole 41 in a wall 42 also a portion of the bearing housing. 40 The walls 42 are surmounted by a roof 43 which together form a housing for the pump. The end of the pump casing which projects through the wall 42 is provided with a flange 44 having holes 45 through 45 which stud bolts are adapted to pass into the wall 42 whereby the pump may be fastened. A plan view of the pump in assembled relation to the bearing housing may be had by reference to Fig. 7, the mode of 50 application of the pump being the same in the modified form of crusher of that figure. The suction side of the pump is connected by means of a pipe 46 through the wall 25 of the bottom plate to the annular well 55 formed by the transverse portions or walls 24, 25 of the bottom plate and the gear 20. The discharge side of the pump is connected by means of a pipe 47 to the central portion 60 of the bottom plate so as to communicate with the oil well formed by the central portion of said plate.

The bottom shell 2 of the crusher (see Figs. 2, 3) is provided with a bifurcated discharge opening comprising the discharge 65 openings 48, 49. These discharge open-

ings are the bottom terminals of the diaphragm 50 (see Fig. 1). Communicating with the two discharge openings are the chutes 51, 52 respectively (see Figs. 2, 3). The chute 51 is provided with an outer, substantially vertical, wall forming part of and merging into the cylindrical portion of the bottom shell 2. The chute 52 is similarly provided with an outer wall 54. These walls are substantially plane and are tangent to the inner cylindrical contour of the bottom shell approximately at the ends of a chord of a length almost equal to a diameter and parallel to the general plane of the discharge openings. The diaphragm includes a semi-annular portion 55 in the rear half of the bottom shell. This semi-annular portion forms an extension of the respective chutes 51, 52, inclined at a slightly greater angle as will be clear from Fig. 1. The inner portion of the diaphragm is bounded by a pipe-like portion 56 of general cylindrical form preferably cast integral with the diaphragm and shell. The crusher shaft is adapted to pass through this pipe-like portion as will be clear from Fig. 1. The general form of the intersection 57 between the pipe-like portion 56 and the semi-annular portion 55 is indicated in Fig. 3. The pipe-like portion 56 is provided with bulges 58, 59 on each side thereof forming conoidal portions tangential to the substantially cylindrical portion of the pipe. The purpose of these bulges is explained in the copending application of A. J. Jorgensen, Serial No. 446,209, filed Feb. 19, 1921. A liner section 60 provided with oppositely inclined surfaces 61, 62 generally of triangular shape is provided at the rear of the pipe 56 and is adapted to rest upon the semi-annular portion 55. This liner section prevents lodgement of crushed material at the rear of the pipe as will be obvious.

The chute 51 is provided with an inside vertical wall 63 extending from the openings 48 to and tangent to the conoidal portion 58. The chute 52 is provided with an inside wall 64 extending from the opening 49 to and tangent to the conoidal portion 59. The walls 63, 64 extend down to the strut 19 and the bearing member 14 and are surmounted by a saddle-like portion 65 comprising oppositely inclined surfaces 66, 67. The saddle-like portion, the walls 63, 64 the pipe 56, the strut and bearing member 14, and bottom shell are cast integral with each other thereby forming a strong strut for the bearing.

The bottom shell 2 is provided with two side openings 68, 70 and a rear opening 69. One of these openings is adapted to receive a bearing, as 32, for the crusher driving shaft, the remaining openings being then closed by cover plates (not shown).

The material discharged from the open-

ings 48, 49 may be directed upon a spout 71 (see Fig. 1), which may be common to the two openings or not, as desired. The surface of this spout is preferably flush with the surface of liners on the diaphragm, indicated by the dotted line 73 (Fig. 1). The saddle 65 may also be provided with a liner 72, but only the liner 60 has been shown in Figs. 2, 3 for the reason that the latter is the only one which functionally changes the effective surface of the diaphragm.

A dust ring 74 surrounding the shaft 4 below the crusher head is adapted to ride on the upper end of the pipe-like portion 56. In order to prevent entrance of dust and other foreign material into the eccentric bearing surfaces and the lubricating oil, a bonnet 75 is provided. This bonnet is provided with a cylindrical portion 76 internally telescopically associated with the eccentric 10. The bonnet is provided with a transverse flange 77 extending over the outer bearing member 13. The outer bearing member may, to the end that the entrance of foreign material will be more effectually prevented, be also provided with an inwardly extending flange 78. In order to prevent the entrance of foreign material between the cylindrical portion of the bonnet and the crusher shaft 4, a dust ring 79 surrounding the said shaft 4 is provided and is formed to extend over said cylindrical portion 76. The bonnet may be rigidly associated in any desired manner with the eccentric and is preferably not in frictional engagement with any of the associated parts, thus reducing wear.

In order to provide for the passage of oil as between the inner and outer bearing surfaces 11, 12 of the eccentric any number of oil passages 80, 81 may be provided. In order to provide for any excess of oil at the upper end of the eccentric and to prevent the overflow thereof on to the bearing support 14, the overflow pipe 82 is provided. The upper end of this pipe passes through the upper end of the outer bearing 13 and the lower end passes through one of the struts 19 where any oil passing through said pipe is discharged onto the surface of the gear 20.

The operation of the crusher illustrated in Figs. 1 to 5 inclusive is as follows:

When the crusher driving shaft 31 is rotated the crusher head is gyrated in the well known manner. Material crushed by this motion drops through the spaces between the crusher head and the concaves on to the diaphragm. Some of this material drops directly onto either the chute 51 or 52 or the semi-annular portion 55. On these parts the material readily slides down and thence through either openings 48 or 49 onto the discharge spout 71. Any material falling upon the saddle-like portion 65 is de-

flected either one way or the other by the oppositely inclined surfaces 66, 67 thereof onto either the chute 51 or 52. Material descending directly at the rear of the pipe 56 will be deflected either one way or the other by the saddle-like liner 60. It will be observed that the construction is such that a clear passage is provided for the material from any point on the diaphragm to one of the discharge openings and that there is no place where material can lodge and clog up the crusher.

In addition to the advantages above noted, the construction involving the double discharge opening permits of disposing the eccentric closer to the diaphragm, on account of the head-room afforded between the inner chute-walls and under the saddle-like portion 65, thus shortening the crusher generally and the bottom shell specifically, while at the same time permitting the desired steepness of incline of the diaphragm.

The rotation of the crusher driving shaft in a predetermined direction causes the operation of the pumps 33 by means of the gear 37 and the pinion 36. It may be stated that the direction of rotation of the pinion 33 should always be the same, the pump being of the gear type and irreversible. The operation of the pump causes oil to be drawn through the pipe 46, through the pump, and forced through the pipe 47 into the well formed by the central portion of the bottom plate 23. Some of this oil is forced up and out between the wearing ring 22 and the gear 20 thus affording efficient lubrication for these parts. The major portion of the oil pumped into the central oil well passes into the recess 27 and as the cover plate 26 is being rotated by the gear 29 the oil in question will be thrown out through the passages 28 by centrifugal force and will be expelled from the openings 29. The pressure of the centrifugal pump will thus be added to that of the gear pump and oil emerging from the openings 29 will be forced between the crusher shaft and the inner bearing 11 of the eccentric, up between these surfaces to and through the passages 80, 81, down between the outer bearing surface of the eccentric and the bearing 13, into the gear 20. The inside of the gear 20 will ordinarily not be filled with oil inasmuch as the latter will be thrown up on the inside surface of the gear by centrifugal force and from thence over the top thereof. From there the oil drops into the annular well formed by the transversely extending walls 24, 25 from where it again enters the pipe 46. If the space at the top of the outer bearing surface of the eccentric and the bearing 13 should become full of oil, the excess will be discharged through the pipe 82 onto the gear 20, as has already been pointed out.

115

120

125

130

It is desirable that it be possible, for various reasons, to change the direction of rotation of the crusher driving shaft. Inasmuch as the shaft of the pump 33 must 5 rotate in the same direction, means must be provided whereby this result may be attained when the direction of rotation of the shaft 31 is reversed. The hereinbefore described mounting for the pump 33 provides 10 a means whereby the direction of rotation of the pump may be readily kept the same. It is only necessary to remove the pinion 36, take out the stud bolts passing through the holes 45 into the wall 42, 15 loosen the pipe connections 46, 47 a predetermined extent, and then rotate the pump 180 degrees so that the end 35 of the pump shaft will assume the position of the end 34 as viewed in Fig. 5. The pinion 36 is then keyed to the end 35 and the 20 stud bolts for holding the pump in position are replaced. The pump is then in the proper relation to the shaft 31 so that the latter may be rotated in the reverse direction.

In case the pump 33 fails to operate for any reason, the centrifugal pump formed in the cover plate 26 is designed to provide sufficient pressure to lubricate the eccentric 30 at least to such an extent as to prevent damage to the rotating parts should the crusher continue in operation. If the centrifugal pump is of sufficient strength to raise oil up to the top of the inner eccentric 35 surface 11 this oil will pass through the passages 80, 81 and as before described will reach the annular well formed by the walls 24, 25. Inasmuch, however, as no oil is being drawn into the pipe 46 the excess oil finds its way into the central well 23 between the wearing ring 22 and the gear 20.

The connection of the rotary pump 33 and the centrifugal pump 26 in series 45 whereby they may assist each other in normal operation is a considerable factor in increasing the reliability of the lubricating system inasmuch as, should the rotary pump fail, the centrifugal pump which it is practically impossible to put out of operation, will furnish sufficient lubrication to prevent damage to the crusher, although of course, ordinarily, the lubrication by the centrifugal pump alone may not be quite 55 so efficient as when the system operates normally.

Referring now to Fig. 6, this figure illustrates a modified form of crusher in which the features of the invention have been 60 embodied, the construction shown being particularly adapted for crushers of larger size. The crusher in question comprises a top shell 83 and a bottom shell 84. The bottom shell is provided with a transversely 65 extending flange 85. The top shell is pro-

vided with a flange 86 adapted to rest upon the flange 85, and the latter flange is adapted to rest upon a foundation or support 87. By this construction the bottom shell 84 supports only its own weight and parts 70 hung therefrom but not the weight of the top shell, the spider, the crusher shaft and crusher head. It may be stated that the movable parts of the crusher disclosed in Figs. 6, 7, and 8 and parts directly associated therewith, including the oil circulating and lubricating system, are the same as in the crusher disclosed in Fig. 1 and these parts, for the sake of brevity, will therefore not be again described and referred to by reference numerals. The weight of the top shell 83, and the parts carried thereby is transmitted through the flange 85 to the foundation 87. In view of this construction it is possible to greatly reduce the size 80 of the bottom shell 84. The diameter of the shell 84 need not be larger than the bottom of the top shell as the broad base provided by the flange 85 provides ample 85 stability; the bottom shell may moreover be made lighter and smaller in another respect as it supports only its own weight 90 and directly associated parts.

Referring now more particularly to Figs. 7 and 8, the bottom shell 84 is provided with a bifurcated discharge opening comprising the openings 88, 89 and another bifurcated discharge opening, located peripherally opposite to the first named bifurcated opening and comprising the openings 90, 91. These bifurcated openings form the bottom terminals of a diaphragm 92. This diaphragm comprises a pair of chutes 93, 94 the lower ends of which terminate at the openings 88, 89 respectively, and a pair of chutes 95, 96 the lower ends of which terminate at the openings 90, 91 respectively. The diaphragm is provided with a pipe-like portion 97 through which the crusher shaft is adapted to pass. The chute 93 is provided with an outer, substantially vertical, wall 98 and the chute 94 is similarly provided with an outer, substantially vertical wall 99. These walls form part of and merge into the cylindrical portion of the bottom shell 84; they are substantially tangent to the inner cylindrical contour of the bottom shell approximately at the end of a chord of a length almost equal to a diameter and parallel to the general plane of the discharge openings. The chutes 95, 96 are similarly provided with outer walls 100, 101. The chute 93 is provided with an inside vertical wall 102, extending from the bottom shell to 100 and substantially tangent with the pipe-like portion 97. The chute 94 is similarly provided with an inside wall 103. The walls 102, 103 are surmounted by a saddle-like portion comprising oppositely inclined surfaces 107, 108 extending from the bottom 105 110 115 120 125 130

shell to the pipe-like portion. The chutes 95, 96 are provided with inside walls 104, 105 extending from the shell between the openings 90, 91 to the pipe-like portion 97 in a manner similar to that described above in connection with chutes 93, 94. The walls 104, 105 are similarly surmounted by a saddle-like portion comprising oppositely inclined surfaces 109, 110. The surfaces of the diaphragm 19 may be provided with liners throughout if desired and of these the liners 111, 112 disposed upon the saddle-like portions are indicated in section in Fig. 6. The surfaces of the liners on the chutes is indicated by the dotted line 113, Fig. 6. Each bifurcated discharge opening may be provided with a spout 114, 115 respectively, and the surface of these spouts is preferably flush with the surfaces 113 of the liners. 20 The operation of the crusher illustrated in Figs. 6, 7 and 8 is as follows:

As far as the action of the moving parts of the crusher is concerned including the lubricating and oil circulating system with 25 its gear pump and centrifugal pump, the operation is the same as that set forth in connection with the crusher of Fig. 1. It will be observed that the oppositely inclined surfaces of the discharge chutes form a 30 ridge 106 and as the material is crushed and drops through onto the diaphragm, a portion thereof will fall on one side of the ridge and a substantially equal portion will fall on the other side of the ridge. Material 35 which drops directly onto the discharge chutes passes freely down the respective chute to the discharge spout; material which drops upon either one of the saddles will be deflected either one way or the other by 40 the oppositely inclined surfaces of the saddle in question and slide freely onto one of the discharge chutes. It will be seen that the two bifurcated discharge openings provide a very large exit opening for the material, particularly in comparison to the size 45 of the bottom shell and that the crushed material has a clear passage from any point on the diaphragm to one of the discharge openings. The foregoing result is accomplished 50 without sacrificing the desired factor of strength in the bottom shell but on the contrary the shell is actually strengthened by the inside walls of the chutes and the saddles surmounting the same forming 55 struts. The use of two bifurcated discharge openings, moreover, permits of a still further reduction in the height of the bottom shell, the reason for this being that the inclined semi-annular portion 55 of the diaphragm (see Fig. 1) is not necessary where 60 two bifurcated discharge openings are utilized so that a large proportion of the vertical height of this inclined surface may 65 be subtracted from the height of the shell.

It should be understood that it is not de-

sired to limit the invention to the exact details of construction herein shown and described, for obvious modifications will occur to a person skilled in the art.

It is claimed and desired to secure by Letters Patent:

1. A crusher comprising a shell having a pair of adjacent openings in said shell wall, a bearing disposed in and adapted to transmit crushing stresses to said shell, and means 75 including a diaphragm within said shell whereby the crushed material descends upon said diaphragm to said openings in a pair of separately maintained streams.

2. A crusher comprising a shell having a 80 pair of adjacent openings in said shell wall, and means including a pair of straight chutes of substantially uniform width whereby the crushed material descends within said shell to said openings in a pair of 85 separately maintained streams.

3. A crusher comprising a shell having a 90 pair of adjacent openings in said shell wall, and means whereby the crushed material descends within and is discharged from said 90 shell through said openings in a pair of separately maintained substantially parallel streams.

4. A crusher comprising a shell having a 95 pair of adjacent openings in said shell wall, means including a pair of chutes whereby the crushed material descends within and is discharged from said shell through said 100 openings in a pair of separately maintained substantially parallel streams, and a saddle-like deflecting member between said chutes.

5. A crusher comprising a shell, and means whereby the crushed material is discharged in a pair of separately maintained 105 adjacent streams including a pair of chutes for carrying said streams, a bearing disposed in and adapted to transmit crushing stresses to said shell, and means for strengthening said shell comprising a strut extending between said chutes from said shell to 110 said bearing.

6. A crusher comprising a shell, and means whereby the crushed material is discharged in a pair of separately maintained 115 adjacent streams including a pair of chutes for carrying said streams, and a bearing disposed in and adapted to transmit crushing stresses to said shell, the inner walls of said chutes forming a strut between said shell and said bearing.

7. A crusher comprising a shell, and means including two pairs of chutes extending from the axis of said shell to the exterior thereof whereby the crushed material is discharged in two substantially oppositely directed pairs of separately maintained adjacent streams.

8. A crusher comprising a shell, means whereby the crushed material is discharged 130 in two substantially oppositely directed

5 pairs of non-converging adjacent independent streams, including two pairs of chutes for carrying said streams respectively, a bearing disposed in said shell, and 5 means for strengthening said shell comprising a continuous member extending between said chutes from one side of the shell to the other.

9. A crusher comprising a shell, means 10 whereby the crushed material is discharged in two substantially oppositely directed pairs of nonconverging adjacent independent streams including two pairs of chutes for carrying said streams respectively, and 15 means for strengthening said shell comprising a continuous member extending between said chutes from one side of the shell to the other, said continuous member forming the inner walls of said chutes.

20 10. A crusher comprising a substantially cylindrical shell having an opening in said shell wall and a straight discharge chute within said shell the outward wall of which is tangent to the inner surface of said shell 25 said chute communicating with said opening.

11. A crusher comprising a bottom shell having a diaphragm and an eccentric bearing, said shell being provided with a flange 30 whereby the same may be supported, and a top shell directly supported by said flange.

12. A crusher comprising a top shell provided with crushing concaves, a bottom shell having a diameter no greater than the bottom of said top shell, a transverse flange on 35 said bottom shell near the top thereof whereby the entire crusher may be supported, said flange directly carrying said top shell.

13. A crusher comprising a comparatively 40 light bottom shell having a diameter no greater than the bottom of said top shell, said bottom shell being provided with two adjacent independent discharge openings, a pair of discharge chutes connected with the 45 respective openings, and means whereby a transverse portion of said bottom shell near the top thereof supports said top shell.

14. A crusher comprising a comparatively 50 light bottom shell having a diameter no greater than the bottom of said top shell, said bottom shell being provided with two

peripherally oppositely disposed pairs of adjacent independent discharge openings, two pairs of oppositely inclined discharge chutes 55 co-operating with the respective pairs of openings, and means whereby a transverse portion of said bottom shell near the top thereof supports said top shell.

15. A crusher comprising a top shell provided with crushing concaves, a bottom shell incapable as a whole of supporting said top shell, a support, and means whereby the entire weight of said top shell is transmitted to said support through a portion of said 65 bottom shell.

16. A crusher comprising a top shell portion provided with crushing concaves, a bottom shell portion provided with a diaphragm for receiving the crushed material, 70 and means for supporting said crusher associated therewith at a point approximately between said shell portions.

17. In a crusher of the type including a shell provided with a diaphragm cooperating 75 with a discharge opening in said shell, said diaphragm including a pipe-like portion, a crusher shaft extending through said pipe-like portion, means within said shell for imparting a gyratory motion to said 80 shaft, said means having portions above the central level of said diaphragm, and means for preventing contact between said portions and said diaphragm while permitting free descent of crushed material from any 85 point on said diaphragm toward said discharge opening.

18. In a crusher of the type including a shell provided with a diaphragm cooperating with a discharge opening in said shell, 90 said diaphragm including a pipe-like portion, a crusher shaft extending through said pipe-like portion, an eccentric within said shell for imparting a gyratory motion to said shaft, means associated with said eccentric and above the central level of said 95 diaphragm for preventing the entry of dust into the eccentric bearing surfaces, and means for preventing contact between said last named means and said diaphragm. 100

In testimony whereof, the signature of the inventor is affixed hereto.

RAY C. NEWHOUSE.
